EVAPORATOR

John J. McAndrews, Hempstead, N. Y.

Application October 20, 1943, Serial No. 506,939

2 Claims. (Cl. 159—23)

This invention relates to evaporators and more particularly to evaporators adapted to be used for procuring water for boilers and other uses on ships and other places.

While quite obviously my evaporator may be used in any number of ways it is particularly adaptable for use in evaporating salt water. With the evaporators now in use considerable difficulty is encountered in cleaning the tubes and in keeping the evaporator in efficient condition. As salt water is evaporated the salt forms a coating on the tubes and other parts of the evaporator which tends to insulate them and generally to cut down the efficiency. It is then necessary to take the evaporator out of service and to manually clean the tubes and other parts.

An advantage of the present invention rests in the simplified method of cleansing the tubes and in removing foreign deposits therefrom.

In the accompanying drawing—

Figure 1 is a side elevation partly in section of an evaporator embodying my invention;

Fig. 2 is an end view thereof;

Fig. 3 is a cross sectional view of the construction of the tubes.

My invention 10 comprises a boiler of any desired shape having a bank of tubes 11 mounted therein. The tube bank is constructed with a double head 12 provided with separate chambers 14 and 15. The tubes 16 are closed at one end 17 and have inner tube members 18 through the open ends 19. Steam is introduced into the chamber 14 through the inlet 25 then passes through the tubes 18 out the end 26 thereof. The steam then passes back through the tubes 16 around the tubes 18 and into the chamber 15 where it passes through the outlet 27 back to the boilers.

The opening 25 is provided with a valve 28 and additional valves may be provided as necessary.

In operation, salt water is introduced into the evaporator 10 up to the level of the tube bank 11. Steam is introduced into the tubes through the inlet 25. A vacuum is maintained within the evaporator and the water will therefore evaporate

below the normal boiling point. As the water evaporates it is taken off through the pipes 30.

When it is desired to clean my evaporator to remove the salt crust from the tube bank 11, steam is introduced into the tubes in the usual way and cold water introduced into the pipe 31. The pipe 31 has a series of openings 32 and is placed over the tube bank. As the cold water is introduced through the pipe 31 it is sprayed through the openings 32 over the entire tube bank, thus suddenly cooling the tubes and causing them to contract. This pulls the tubes away from the salt crust and causes it to break and fall off into the bottom of the evaporator. It may then be cleaned out through the port 35 or the opening 36 and it is not necessary to manually remove the salt crust from the tubes.

My evaporators may be used with high or low pressure and two or more evaporators may be connected in a series.

I claim:

1. An evaporator comprising a vacuum chamber, a bank of horizontally disposed tubes within said chamber, said tubes being closed at one end 25 thereof, a plurality of pipes, one in each of said tubes, means for introducing steam into said tubes through said pipes, means for removing deposits on said tubes, said latter means including a cold water spray positioned above said tubes for suddenly contracting said tubes beyond the contracting limit of said deposits.

2. An evaporator including a vacuum chamber, a plurality of tubes horizontally mounted in said chamber, said tubes being closed at one end and having their open end connected to a common head, a second head, a plurality of pipes mounted in said second head and extending through said first-mentioned head into said tubes, one pipe in each of said tubes, means for introducing steam through said pipes into said tubes and means for suddenly contracting said tubes beyond the contracting limit of salt crust, said means comprising a cold water spray positioned over said tubes.

JOHN J. McANDREWS.
